UNITED STATES PATENT OFFICE.

GEORGE C. LUCAS, OF CLEVELAND, OHIO.

DESIGN FOR A GUARD FOR RAILROAD-FROGS, &c.

SPECIFICATION forming part of Design No. 27,655, dated September 21, 1897.

Application filed June 9, 1897. Serial No. 640,075. Term of patent 3 $\frac{1}{2}$ years.

To all whom it may concern:

Be it known that I, GEORGE C. LUCAS, of Cleveland, Cuyahoga county, Ohio, have invented and produced a certain new and useful Design for Foot-Guards for Railway-Frogs, Switches, &c., of which the following is a specification, reference being had to the accompanying drawings, that form part of this specification.

The foot-guard is made of a single metallic bar; and my design consists in the peculiar shape given to this bar by swaging or bending. The bar is set on edge and is bent, as required, to form a head or member a, arranged transversely of the device. Said member a is arranged diagonally as well as transversely and at one end terminates in a U-shaped bend b, and the rear member of said U-shaped portion extends inwardly, parallel with member a, adjacent to the central portion of the rear side of the head, and thence the bar extends a suitable distance 25 rearwardly and longitudinally, and at its rear end is offset laterally, as at d.

The essential features of my design consist in the U-shaped bend that connects the transversely-arranged head or member with the 30 rearwardly and longitudinally extending member and the lateral offset of the rear end of said longitudinally-arranged member.

What I claim is—

The design for a railway foot-guard, substantially as shown and described. 35

In testimony whereof I sign this specification, in the presence of two witnesses, this 12th day of May, 1897.

GEORGE C. LUCAS.
